(57) **CLAIM**

The ornamental design for a pacifier holder, as shown and described.

DESCRIPTION

FIG. 1 is a top, front, right perspective view of a pacifier holder, showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof;

FIG. 7 is a left side elevation view thereof; and,

FIG. 8 is a top, front, right perspective view of the pacifier holder of FIG. 1, shown in an alternate configuration for use, for clarity of disclosure.

In the drawings, the equal-length broken lines showing a zipper and zipper pull depict portions of the pacifier holder that form no part of the claimed design. The dash-dot-dash broken lines on the pacifier holder exterior depict a surface pattern that forms no part of the claimed design.
